(57) **CLAIM**

The ornamental design for a buckle for a stirrup strap, as shown and described.

DESCRIPTION

FIG. 1 is a perspective view of a buckle for a stirrup strap showing my new design.

FIG. 2 is a top plan view thereof.

FIG. 3 is a front elevational view thereof.

FIG. 4 is a side elevational view thereof.

FIG. 5 is a rear elevational view thereof.

FIG. 6 is a side elevational view of a side opposite that shown in FIG. 4; and,

FIG. 7 is a bottom plan view thereof.

The broken lines in the drawings are for the purpose of illustrating environment only and form no part of the claimed design.
